UNITED STATES PATENT OFFICE.

FRANK J. KARKOSKA, OF DETRCIT, MICHIGAN.

EXTENSION HANDLE FOR NONLIFTING INJECTOR-STARTING VALVES.

Application filed January 25, 1927. Serial No. 123,439.

My invention relates to an extension handle for non-lifting injector starting valves on locomotives, and aims to provide a novel and improved device of this character for use in connection with modern locomotives having the starting valve arranged exteriorly with respect to the cab, said valve in the present instance being provided with means whereby it may be conveniently operated in an efficient manner.

Another object of the invention is to provide an extension handle for the purpose mentioned above for controlling the starting valve, which will eliminate all danger of the valve closing due to vibration while the locomotive is in operation, as often occurs with extension handles now commonly used, such closing being quite dangerous as it permits the escape of water which might cause the blowing up of the boiler.

A further object of the invention is the provision of an extension handle or operating rod and bracket for attachment to the lever of the starting valve, said bracket slidably supporting the operating rod having a handle positioned within easy reach from within the cab and the rod being adapted to be forced against spring tension into engagement with a trigger on the valve lever in order to release the lever and permit the same to be moved forwardly, rearward movement being effected by merely pulling on the handle.

It is also an object of the invention to provide a device of the above indicated character, which is simple and substantial in construction, can be manufactured economically, and will be thoroughly efficient and practical in use.

With the foregoing and other objects in view, which will be apparent as the description proceeds, the invention resides in the construction and arrangement of parts, as herein-after described and claimed, it being understood that immaterial changes can be made within the scope of what is claimed, without departing from the spirit of the invention.

The invention is illustrated in the accompanying drawings, wherein:

Figure 1 is a fragmentary vertical section through a non-lifting injector starting valve, showing my improved extension handle connected to the lever of the valve,

Figure 2 is a fragmentary vertical section through the forward end of my improved extension handle and through a portion of the lever of the valve, and

Figure 3 is a plan view of my improved extension handle.

Referring to the drawings, the numeral 10 designates a non-lifting injector starting valve having a pivoted lever 11 for operating the valve in order to govern the amount of steam admitted through the same, said lever having thereon a pivoted pawl 12 for engaging a notched quadrant 13 for holding the lever in a position with the valve open. Attached to the pawl is a rod 14 extending upwardly through the offset upper portion 15 of the lever with a coil spring 16 encircling the rod and seated in a recess in said offset portion to bear against a head 17 on the rod for actuating said rod to normally hold the pawl in engagement with the notched quadrant. Pivoted in the upper end of the lever 11 by pin 22 is a trigger 18 in engagement with the head 17 on the rod 14 and having a depending arm so that upon forcing said trigger arm towards the lever 11, the rod will be forced downwardly against the action of the spring and thus lift the pawl 12 from the notched quadrant 13. When the pawl is disengaged from the quadrant the lever 11 is released and may be moved forwardly. The construction so far described is that of a well known type of starting valve and forms no part of my invention.

In carrying out my invention I provide a U-shaped bracket 20 presenting spaced apart members for supporting a cross-pin 22 which takes the place of the pin usually employed for pivotally mounting the trigger 18 in the upper end of the lever 14. The bight portion of the U-shaped bracket is enlarged, as at 23, and provided with a longitudinal opening 24 extending therethrough, and slidably mounted in this opening is an operating rod 25 provided at its inner end with a downwardly projecting arm 26, contiguous to the trigger-arm 18 and adapted to be forced into engagement therewith for swinging the trigger on its pivot. Arranged about the rod 25 beyond the bracket is a coil spring 27 interposed between the bracket 20 and a collar 28 on the rod, said collar being held against movement on the rod by means of a cotter pin 29, and for convenience in operating the rod it is provided with a looped handle 30. It will be noted that the spring normally holds the depending arm 26 of the operating rod out of engagement with the trigger-arm 18 and thus avoids operation of said trigger-arm until pressure is applied on the rod for sliding the same in

the bracket 20 against the action of said spring.

The rod 25 is of a length sufficient to permit the convenient operation of the valve from the cab seat of a locomotive, and may have any type of bearing at its rear end for preventing the same from swinging downwardly and operating the trigger due to its weight. In modern locomotives as now constructed, the valve is located outside the cab at a position inconvenient for operation by the engineer from the cab seat, and by providing my improved form of extension handle and cooperating devices the valve may be conveniently manipulated in a safe manner.

The operation of my improved extension handle is very simple, the valve being opened by merely grasping the handle 30 and pulling on the same until the valve is open to its desired position when the pawl on the lever will engage in a notch in the quadrant and thus hold the valve in such open position. To close the valve the handle is pushed forward causing the spring 27 to be slightly compressed until the arm 26 at the inner end of the rod engages the trigger-arm 18 and swings the trigger on its pivot thus forcing the connecting rod 14 downwardly and disengaging the pawl 12 so that further forward movement of the operating rod will actuate the valve-lever 11 to close the valve.

It is to be noted that the coil spring 27 is sufficiently strong to prevent any vibration of the locomotive when in operation being communicated to the valve operating mechanism and cause operation of the trigger. In practice it has been found that the extension handles for valves now commonly used will turn under the influence of the vibration of the locomotive until the locking mechanism employed in connection with the lever 11 is released permitting the valve to close. Valve operating means of this kind are therefore dangerous as water may escape to such an extent as to cause injury to the boiler. From the foregoing, it can be seen that I have provided an extension handle which may be operated in the same manner as by grasping the valve-operating lever 11 directly, and as my improved valve operating means is employed in connection with the usual operating means of the valve it may be applied without any material alteration in the same, particular attention being called to the fact that in the present instance it is necessary to overcome the tension of the spring 27 in order that the arm 26 may be moved to operate the trigger,

preventing said trigger from being operated by vibration.

Having thus described my invention, what I claim as new is:

1. An extension handle for locomotive valves in combination with a lever having a release member thereon, a U-shaped bracket attached to said handle with the release member located between the spaced apart members thereof, a rod slidably carried by said U-shaped bracket, a member on said rod for actuating said release member in one direction, spring means for actuating said member in the other direction or normally out of engagement with said release member, and a handle on the free end of said rod for manipulating the same in said bracket to release said release member and to swing the lever on its pivot.

2. An extension handle for locomotive valves in combination with a lever having a release member thereon, a U-shaped bracket having the spaced apart members thereof attached to the opposite sides of said lever and with the release member located between said bracket members, said U-shaped bracket having a bore in the bight portion thereof, a rod slidably mounted in said bore, an arm on the inner end of the rod depending from between the members of the bracket, a coil spring on the rod interposed between the bracket and a collar fixed on said rod for normally holding said arm out of engagement with said release member, and a handle on the free end of said rod for sliding the same in the bracket to actuate the release member and for swinging the lever on its pivot.

3. An extension handle for locomotive valves in combination with a lever having a pivoted release member thereon, a U-shaped bracket having the spaced apart members thereof at opposite sides of said lever and connected to said lever by means of the pivot pin which pivotally supports the release member, said release member being arranged between the members of said U-shaped bracket, a rod slidably mounted in said bracket, an arm on the inner end of said rod for engaging said release member, spring means for normally holding the rod with the arm out of engagement with said release member, and a handle on the free end of said rod for sliding said rod to engage the arm at the inner end thereof with said release member and for swinging said lever on its pivot.

FRANK J. KARKOSKA.
